UNITED STATES PATENT OFFICE.

CENTENNIAL W. JERRY, OF CUMBERLAND, WISCONSIN.

ATTACHMENT FOR WHEELED SCOOPS OR SCRAPERS.

Application filed October 17, 1921. Serial No. 508,417.

To all whom it may concern:

Be it known that I, CENTENNIAL W. JERRY, a citizen of the United States, residing at Cumberland, in the county of Barron and State of Wisconsin, have invented a new and useful Improvement in Attachments for Wheeled Scoops or Scrapers, of which the following is a specification.

My invention relates to improvements in attachments for wheeled scoops or scrapers of the conventional type having a scoop mounted upon wheels, provided with the usual raising and dumping lever, and draft mechanism; and the objects of my improvement are, first, to provide an attachment whereby the scoop may be readily adapted for gathering stones or similar objects; second, the provision of means for the control and regulation of the scoop when the attachment is in use; third, the provision of means for the control of the scoop while operating with the attachment in soft loose earth; and fourth, to provide a device which is specially adapted to gather stones upon roads.

I attain these and other objects and advantages by the mechanism illustrated in the accompanying drawing, in which—

Figure 1 is a side elevation of a scoop with my attachment in place, parts being removed and broken away to show the novel structure;

Figure 2 is a top plan of a scoop provided with my attachment, parts being broken away to more clearly show the structure;

Figure 3 is a side elevation of a pan or scoop, a portion of the side wall being broken away and the pivoted finger bar latched in upright position;

Figure 4 is a rear elevation of a portion of the finger bar and an end finger which is detachably secured thereto and provided with a lever arm and gudgeon;

Figure 5 is a side elevation of the end finger shown in Fig. 4;

Figure 6 is a top plan of the end finger shown in Fig. 4;

Figure 7 is an end elevation of the finger bar;

Figure 8 is a top plan of a portion of one end of the finger bar;

Figure 9 is an elevation of a portion of

the front end of the side wall of the scoop; and

Figure 10 is a section on the line 10—10 55 of Fig. 3 looking in the direction of the arrows, the link 11 being removed.

Similar numerals refer to similar parts throughout the several views.

In the preferred form of my invention I 60 provide a wheeled scoop having a scoop or pan 1, raising and dumping lever 2, wheels and axle 3, and draft mechanism 4, with a finger bar 5, having gudgeons 7 adapted to fit and pivot in apertures 6 suitably placed in 65 the lower front ends of the side walls of the pan so that when the bar is in position for gathering it will lie flat upon and be supported by the bottom of the pan.

The gudgeon 7 at one end of the bar 5 is 70 formed integrally therewith, and at the other end of the bar the end finger or tine 8, which is detachably secured to the bar 5 by means of bolts 10, is formed with a suitable body portion adapted to fit over the 75 end and upper side of the finger bar; projecting from the rear end of the body portion at right angles thereto, in line with the bar and the gudgeon formed at its opposite end, is a gudgeon 7; from the front end of 80 the body portion the finger 8 extends forwardly and downwardly below the bar and the front edge of the bottom of the scoop and then forwardly parallel to the plane of the body portion; forwardly and upwardly 85 extending from the front end of the body portion is a curved lever arm 9 which is adapted to be pivotally connected with the actuating mechanism.

A series of fingers or tines 8, suitably 90 spaced, is secured to the upper side of the bar 5, these fingers are formed to project downwardly and forwardly below the bar 5 and the front edge of the bottom of the pan, and then forwardly parallel to the planes of 95 the bar and the bottom of the pan, as shown in Figure 1.

Pivotal secured to the lever arm 9 is a link 11, extending rearwardly along the side wall and slidably through an aperture 100 22 in the rear wall of the pan. The outer end of the link 11 is pivotally connected to a link 12, the opposite end of which is pivotally secured to one arm of an angle lever

13, which is pivotally secured to the side wall of the pan by means of a bracket 21. The free end of the angle lever extends so as to be easily accessible to the operator, 5 and may be operated in any suitable manner as by the foot or hand of the operator.

A spring 14 secured to the side wall of the pan and to the lever 13 serves to draw and hold the lever forward, and through the 10 connecting links 11 and 12, to return and assist in keeping the finger bar in gathering position.

A notch 15 in the link 11 is adapted to be engaged by a latch 16, pivoted to the outside 15 of the rear wall of the pan adjacent the aperture 22, to hold the finger bar in the position shown in Figure 3.

Shoes 17 are detachably secured to the bottom of the pan by means of bolts 18, and 20 serve to prevent the pan from gouging or entering the ground when the attachment is in use.

For convenience in assembly and detachment the pivotal connections and mountings 25 of the operating levers and links are made by means of bolts 23.

A series of catches 19 is secured to the rear wall of the pan and adapted to be engaged by the latch 20 on the raising and dumping 30 lever 2.

In gathering stones the latch 20 is released and the pan 1 lowered so that it rests upon the shoes 17, the device is then drawn along with the fingers or tines 8, raking the surface 35 of the ground and gathering stones or other objects upon their upper surface, the dirt and loose fine material pass between the straight portion of the fingers and also between the downwardly bent portions beneath 40 the bottom of the pan; from time to time as the stones are gathered upon the fingers 8, the lever 13 is actuated tilting the finger bar up and throwing the stones gathered upon the fingers back into the pan, this tilting action 45 also effects a further separation of the stones from the dirt and fine material which passes between the fingers as they are raised; when the pan is filled it is raised by means of the lever 2 and held in raised position by 50 the latch 20 engaging the catch 19, the device is then drawn to the place where the stones are to be deposited and dumped the same as the conventional wheeled scoop, by raising the lever 2 as it is drawn along.

55 In order to retain the load in the pan when it has been filled full and is to be drawn some distance, the finger bar may be tilted up to form a side or closure for the front of the pan, and latched in raised position by 60 engaging the latch 16 in the notch 15 of the link 11.

In operating the device in soft or loose ground where the shoes will not support the pan above the surface, the pan may be raised 65 so that its weight is borne upon the wheels

of the scoop, and the depth to which the wheels sink into the earth will determine the appropriate catch of the series 19, with which the latch 20 should be engaged to hold the pan in proper position.

70 My device is specially adapted for road work, as it can be applied to any of the wheeled scoops customarily used therein, quickly converting it into a stone gatherer, adapted for use on either hard or soft or 75 loose ground.

The connecting means employed with my attachment for converting the scoop into a stone gatherer, in no way weaken the scoop or interfere with its ordinary operation, 80 and the shoes, finger bar and operating mechanism can be readily disconnected and detached, and the scoop again used in the customary manner.

85 While I have shown and described specific structures for accomplishing the desired objects, my invention contemplates broadly the use of means operating in the same manner to produce the results desired, and is to be understood as limited only by 90 the state of the art.

I claim:

1. The combination, of a wheeled scoop, a finger-bar pivoted to the front end of the scoop and provided with a lever arm, a 95 link pivotally connected to said lever arm, an angle lever pivoted to the side of the scoop, a link pivoted to one arm of the angle lever and the end of the first mentioned link, whereby the finger-bar may be 100 caused to turn on its pivot by means of the angle lever.

2. The combination, of a wheeled scoop having means for raising the scoop and a latch for holding it in raised position, means 105 for gathering stones, means for preventing the scoop and stone gathering means from entering the ground, and a series of catches adapted to be engaged by the latch for controlling the operation of the device in loose 110 ground.

3. The combination, of a wheeled scoop, a finger-bar pivotally secured adjacent the bottom of the scoop at the front end thereof having downwardly and forwardly projecting fingers and a lever arm, means connected with the lever arm for pivotally actuating the finger-bar, and means for returning and holding the finger-bar and actuating means 115 to normal position.

4. In an attachment for wheeled scoops, a finger-bar, means for actuating the finger-bar, means for returning and holding the actuating means and finger-bar to normal position, shoes for the scoop, and a series of 120 catches for holding the scoop at various heights.

5. In a stone gathering attachment for wheeled scoops, the combination, of a finger-bar having a gudgeon at one end adapted to 130

- enter an aperture in the side wall of the scoop, a series of fingers secured to the bar, an end finger for the bar provided with a gudgeon adapted to enter an aperture in the opposite wall of the scoop and having a lever arm, and means for detachably securing the end finger to the bar. 55
6. In an attachment for wheeled scoops, a bar member, an end finger provided with a gudgeon and having a lever arm, and means for detachably securing the finger to the bar at its end. 60
7. In an end finger for stone-gathering attachments for wheeled scoops, the combination of a body portion adapted to be secured to a finger-bar, a finger member extending downwardly and forwardly below and then forwardly and parallel to the body portion, a gudgeon extending at right angles from the rear end of the body portion, and a curved lever arm extending forward and upward from the front end of the body portion adapted to be pivotally connected to a link member. 65
10. In an end finger for stone-gathering attachments for wheeled scoops, the combination of a body portion adapted to be secured to a finger-bar, a finger member extending downwardly and forwardly below and then forwardly and parallel to the body portion, a gudgeon extending at right angles from the rear end of the body portion, and a curved lever arm extending forward and upward from the front end of the body portion adapted to be pivotally connected to a link member. 70
15. In a wheeled scoop, the combination of, a finger-bar pivoted in the side walls of the scoop and adapted to lie flat upon and be supported by the bottom of the scoop, fingers secured to the upper side of the bar extending forwardly and downwardly below the bar and the front edge of the bottom of the scoop and then forwardly parallel to the plane of the bar, and means whereby the bar may be disconnected and removed from the scoop. 75
20. In an end finger for stone-gathering attachments for wheeled scoops, the combination of a body portion adapted to be secured to a finger-bar, a finger member extending downwardly and forwardly below and then forwardly and parallel to the body portion, a gudgeon extending at right angles from the rear end of the body portion, and a curved lever arm extending forward and upward from the front end of the body portion adapted to be pivotally connected to a link member. 80
25. In a wheeled scoop, the combination of, a finger-bar pivoted in the side walls of the scoop and adapted to lie flat upon and be supported by the bottom of the scoop, fingers secured to the upper side of the bar extending forwardly and downwardly below the bar and the front edge of the bottom of the scoop and then forwardly parallel to the plane of the bar, and means for tilting the bar on its pivots. 85
30. In a wheeled scoop, the combination of, a finger-bar pivoted in the side walls of the scoop and adapted to lie flat upon and be supported by the bottom of the scoop, fingers secured to the upper side of the bar extending forwardly and downwardly below the bar and the front edge of the bottom of the scoop and then forwardly parallel to the plane of the bar, and means for tilting the bar on its pivots, and means for latching the bar in raised position. 90
35. In a wheeled scoop, the combination of, a finger-bar pivoted in the side walls of the scoop and adapted to lie flat upon and be supported by the bottom of the scoop, fingers secured to the upper side of the bar extending forwardly and downwardly below the bar and the front edge of the bottom of the scoop and then forwardly parallel to the plane of the bar, and means for tilting the bar on its pivots, and means for latching the bar in raised position. 95
40. In a wheeled scoop, the combination of, a finger-bar pivoted in the side walls of the scoop and adapted to lie flat upon and be supported by the bottom of the scoop, fingers secured to the upper side of the bar extending forwardly and downwardly below the bar and the front edge of the bottom of the scoop and then forwardly parallel to the plane of the bar, and means for tilting the bar on its pivots, and means for latching the bar in raised position. 100
45. In a wheeled scoop, the combination of, a finger-bar pivoted in the side walls of the scoop and adapted to lie flat upon and be supported by the bottom of the scoop, fingers secured to the upper side of the bar extending forwardly and downwardly below the bar and the front edge of the bottom of the scoop and then forwardly parallel to the plane of the bar, and means for tilting the bar. 105
50. In a wheeled scoop, the combination of, a finger-bar pivoted in the side walls of the scoop and adapted to lie flat upon and be supported by the bottom of the scoop, fingers secured to the upper side of the bar extending forwardly and downwardly below the bar and the front edge of the bottom of the scoop and then forwardly parallel to the plane of the bar, and means for tilting the bar. 110

CENTENNIAL W. JERRY.
